CLAIM

The ornamental design for a combined ceiling fan light glass and motor housing, as shown and described.

DESCRIPTION

FIG. 1 is a top perspective view of a combined ceiling fan light glass and motor housing, showing our new design; FIG. 2 is a bottom perspective view of the combined ceiling fan light glass and motor housing of FIG. 1; FIG. 3 is a top view of the combined ceiling fan light glass and motor housing of FIG. 1; FIG. 4 is a bottom view of the combined ceiling fan light glass and motor housing of FIG. 1; FIG. 5 is a front view of the combined ceiling fan light glass and motor housing of FIG. 1, with the rear view being identical thereto; and, FIG. 6 is a right side view of the combined ceiling fan light glass and motor housing of FIG. 1, with the left side view being identical thereto.

The broken lines illustrate portions of the combined ceiling fan light glass and motor housing and environmental structure. None of the broken lines form part of the claimed design.
